Primary Examiner — John A Voytek(74) *Attorney, Agent, or Firm* — Nixon & Vanderhye(57) **CLAIM**

The ornamental design for a tire, as shown and described.

DESCRIPTION

FIG. 1 is a front and side perspective view of a tire showing the new design, wherein the rear and opposite side perspective view appears the same;

FIG. 2 is a front elevation view thereof, wherein the rear elevation view appears the same; and,

FIG. 3 is a side elevation view thereof, wherein the opposite side elevation view appears the same in mirror image.

1 Claim, 3 Drawing Sheets**FIG. 1**

FIG. 2

FIG. 3
